UNITED STATES PATENT OFFICE.

NICOLAS EMILIEN METHLIN, OF PARIS, FRANCE, ASSIGNOR TO SCHNEIDER & CIE., OF PARIS, FRANCE, A LIMITED JOINT-STOCK COMPANY OF FRANCE.

PIECE OF ORDNANCE MORE PARTICULARLY ADAPTED FOR FIRING UPON AIRCRAFT.

Application filed October 15, 1927, Serial No. 226,354, and in France May 11, 1927.

The present invention has for its subject a particular embodiment of the anti-aircraft gun forming the subject of U. S. patent application filed on 2nd December, 1925 5 (72,743) and U. S. Patent No. 1,658,005.

This embodiment is illustrated in longitudinal elevation with a part in section in Fig. 1, and in plan view in Fig. 2, the gun being shown in these two figures in the position it 10 occupies for transport.

Fig. 3 is a sectional elevation along the line 3—3 in Fig. 1.

The gun comprises a cradle B journalled at its rear end b in bearings d, d^1 carried by a 15 support D movable about a pivot, the oscillating mass being wholly supported on account of the connection of the cradle, at a point near the centre of gravity of the said mass, to a spring-counterbalancing device 20 I—K, journalled in such a way that for any angle of inclination of the mass balance is obtained in practice.

As in the forms described in the above named patent, the platform D, supporting 25 the oscillating mass is constructed in the form of a top carriage adapted to turn in a saddle D^2 , itself movable by means of a ball joint in a pedestal D^3 .

According to the present invention this 30 pedestal is carried in the frame of a tractor or other vehicle, the ball joint for the saddle being disposed in the frame in such a way that the centre of gravity of the whole of the gun which is carried upon the tractor is located, during transport, near the vertical line 35 passing through the centre of gravity of the said tractor.

In the example shown in the drawing the tractor comprises a frame E mounted at the 40 front end upon a set of wheels F, which may be steering wheels, and at the rear end upon endless chains or caterpillar tracks G, steering and driving for example, of any known type.

45 For transport the oscillating mass is brought into the position shown in the figures, the cradle being provided with a member for hooking it upon or disengaging it from the vehicle, for example, upon the apron H.

The latter may comprise a T-shaped groove h in which engages a beak b^1 of cor-

responding shape on the cradle; this engagement of these two parts holds the oscillating mass in the transverse direction. The weight 55 of the oscillating mass may also be taken by a strut I adapted to be lowered.

The whole of the gun thus constructed permits firing to be carried out with a gun barrel recoiling entirely above the frame of 60 the vehicle, the trunnions of the oscillating mass being however, at a small height above the ground. The change over from the firing position to the transporting position is effected with the greatest ease with no other 65 operation than that of hooking the cradle upon the vehicle, and if desired taking the weight of the oscillating mass by raising the strut, I, which is normally lowered. The constant balance of the gun by the spring- 70 counterbalancing device which supports the oscillating mass permits the stability of the gun during firing to be ensured without the use of heavy additional supports.

Provision may naturally be made, as shown 75 in the drawings, of light auxiliary supports of known type, such as those shown at J in the drawings.

Claims:

1. The combination of a tractor and a 80 frame carried thereby, with a pedestal mounted in said frame, a saddle having a ball joint connection with said pedestal, a top carriage adapted to turn in said saddle, a cradle having bearings in said saddle about 85 which it oscillates, a gun mounted for recoil in said cradle, a spring counter-balance on said top carriage, connections from said counter-balance to said cradle at approximately the center of gravity of the mass turning about the cradle bearings, said ball joint and pedestal being located in said frame so as to place the center of gravity of the whole gun approximately in a vertical line passing through the center of gravity of the tractor. 90

2. The combination of a caterpillar tractor and a frame carried thereby, with a pedestal mounted in said frame midway between the caterpillar treads and in a vertical transverse plane passing through said treads where 100 they contact with the ground, a saddle having a ball joint connection with said pedestal, a top carriage adapted to turn in said saddle, a cradle having bearings in said saddle,

idle about which it oscillates, a gun mounted for recoil in said cradle, a spring counterbalanced on said top carriage, connections from said counter-balance to said cradle at approximately the center of gravity of the mass turning about the cradle bearings, the center of gravity of the whole gun being approximately in a vertical line passing through the center of gravity of the tractor.

3. In a construction as defined in claim 1, ¹⁰ a cradle rest on the tractor frame forward of the cradle bearings, and a strut connecting said cradle and frame intermediate said rest and bearings.

In testimony whereof I have signed this ¹⁵ specification.

NICOLAS EMILIEN METHLIN.
